[57] **CLAIM**

The ornamental design for an electronic calculating machine, as shown and described.

DESCRIPTION

FIG. 1 is a perspective view taken generally from a frontal side angle illustrating the electronic calculating machine showing my new design, the same being shown in an open position;

FIG. 2 is a perspective view showing the same in a closed state thereof;

FIG. 3 is a left side elevational view thereof;

FIG. 4 is a rear elevational view thereof;

FIG. 5 is a front elevational view thereof;

FIG. 6 is a bottom view thereof;

FIG. 7 is a plan view thereof;

FIG. 8 is a left side elevational view in an operative state thereof;

FIG. 9 is a rear elevational view in an operative state thereof;

FIG. 10 is a front elevational view in an operative state thereof;

FIG. 11 is a bottom view in an operative state thereof; and

FIG. 12 is a plan view in an operative state.

The broken line disclosure of the display numerals in FIG. 1 is for illustrative purposes and forms no part of the claimed design.
